UNITED STATES PATENT OFFICE.

FRANK SHUMAN, OF PHILADELPHIA, PENNSYLVANIA; Y. JOSEPHINE SHUMAN AND CHARLES H. DUNKER, ADMINISTRATORS OF THE ESTATE OF SAID FRANK SHUMAN, DECEASED, ASSIGNORS TO LOUIS J. KOLB, OF PHILADELPHIA, PENNSYLVANIA, TRADING AS SAFETEE GLASS COMPANY.

DANGER SIGNAL.

1,420,345.

Specification of Letters Patent. Patented June 20, 1922.

Application filed March 23, 1916. Serial No. 86,175.

To all whom it may concern:

Be it known that I, FRANK SHUMAN, a citizen of the United States, and resident of Philadelphia, county of Philadelphia, and 5 State of Pennsylvania, have invented an Improvement in Danger Signals, of which the following is a specification.

The object of my invention is to provide a construction of signal sign and light which 10 shall be especially suitable for railroad crossing gates or the like, in which, when the gate is closed, the danger signal will be shown in the form of an illuminated danger sign, preferably of a red transparency with 15 white or clear letters, such as "Stop" or "Danger" thereon; and which, when the gate is open, will bring into view a clear or white light and remove the illumination from the red or danger sign, so that the same is practically invisible at night. In this way, 20 automobile drivers approaching a railroad crossing can quickly discern the condition of the gate and can depend upon the red danger or white safety light signals, since their respective presence is dependent upon whether the 25 gate is down or up and are essentially automatic in their showing.

With the usual practice at the present time of hanging a red lantern upon the gate, the 30 driver of an automobile, traveling at a relatively high speed, not knowing that a railroad crossing is at hand, is liable to take the signal as indicating a hole or defect in the roadway, and in merely swerving aside 35 to avoid the supposed hole, crashes into the gate. By my invention there can be no mistake, for the red lighted sign is large and with clearly readable words indicating danger and could not be mistaken for a small 40 lantern; whereas when the gate is open, the red light has disappeared and a high positioned white light alone is visible, acting as a caution signal.

My invention consists in forming the 45 danger sign transparency of relatively non-breakable construction by forming it of a metal frame in which is fastened a sign made of an integral structure comprising two sheets of glass united by an interposed 50 layer of celluloid firmly uniting the glass sheets and preferably containing the color and letters to be illuminated, the celluloid

acting to hold the glass together even if it should be cracked by flying missiles or other cause. My invention further consists in the 55 construction of the transparency of greater width than the lantern which is associated with it for illuminating purposes, and in so forming the lantern that it not only sends direct rays through the transparency, but 60 also oblique reflected rays so that the entire width of the transparency is illuminated.

The invention also comprehends other features of construction which, together with those above specified, are hereinafter 65 set out and defined in the claims.

Referring to the drawings:—Fig. 1 is a railroad crossing gate in closed position and having my danger sign applied thereto; Fig. 2 is the same gate when in raised 70 or open condition; Fig. 3 is an enlarged view of a part of the gate, having my invention applied thereto, looking from the rear or railroad side; Fig. 4 is a sectional view of the same, taken on line $x-x$ of Fig. 75 3; Fig. 5 is a section plan view of the lamp; Figs. 6 and 7 are views corresponding to the closed and open gate positions and showing a modification of my invention; and Fig. 8 is an edge view of the indestructible 80 sign transparency.

2 is the gate arm and may be pivoted upon the standard or gear box 3 and adapted to be raised or lowered as in any of the railroad crossing gates heretofore in use. 85 Near the free end of the gate is secured the danger transparency 4, which is preferably of a construction fixedly attached on the arm 2; and back of this transparency is a lantern 5, hung from a supporting bracket 90 or arm 6, whereby it may swing back of the transparency when the gate is down, as shown in Figs. 1 and 3, and to one side of the transparency into full view when the gate is raised, as in Fig. 2. To enable this 95 swinging of the lantern from a position back of the transparency when the gate is down and to a position to one side of the transparency when the gate is raised, it is necessary to provide the hinge or pivot 6 for 100 the lantern 5 to a point to one side of the area of the transparency. As shown, this is located above the transparency to a distance at least equal to one-half the width.

of the lantern so that when the gate is raised into a vertical position, as shown in Fig. 2, the lantern in hanging downward is wholly to one side of the transparency, the hinge point always remaining above the lantern but being above the transparency when the gate is lowered and laterally with respect to the transparency when the gate is raised.

10 I do not restrict myself to the particular details of construction of the transparency nor of the lantern nor of the connections whereby the lantern is allowed to swing, but I have shown a construction by way of 15 example which I deem well suited for the commercial application of my invention. As shown, there is a rectangular frame 4 formed of angle iron 7, and this frame-work has the extensions 8 which are bolted at 9 to 20 the gate timber 2, as clearly shown in Figs. 3 and 4. The transparency 10 is clamped in position upon the angle iron 7 of the frame 4 by means of angle-iron clamping strips 7^a held in position by screws 7^b or 25 otherwise, as preferred. The transparency may be simply a piece of red glass with or without words, such as "Stop," the glass being suitably embedded in putty or otherwise within the metal frame. In the preferred 30 construction of transparency, I make it of two layers of glass 12 with an intermediate layer of celluloid 11, the latter by having its surfaces heated and compressed between the two outer layers of glass forming 35 a union between the latter to provide a composite transparency which is practically indestructible under any normal usage, and which if cracked will not fall out of the frame. The outer glass plates 12 may be 40 transparent white rolled plate, and the celluloid may be red or colored to suit the requirements. Moreover, the celluloid may be printed or stained or otherwise formed with the word "Stop," or any other suitable word, 45 formed without color so that the light shining through the transparency will give the desired ground color with the transparent word. It is manifest that the word may be the colored portion and the rest of the 50 celluloid or intermediate binder may be transparent without color. It will also be understood that while the celluloid acts as a binder between the two glass plates 12, the color may be in one of the glass plates 55 just as if a red glass were employed by itself, and with the word ground thereon so as to have it appear as white letters upon a red ground. I do not limit myself to any of these particular changes in the form of the 60 transparency, nor to the use of celluloid as distinguished from some other binding means between the glass such as gelatin, but in all cases the transparency is to indicate the danger when the light shines through it.

65 The lantern 5 may be of any suitable construction and provided on the inside with suitable reflecting surfaces 15 and at front with a glass door 16, the construction being such that the light through the lamp 14 may send forth direct rays as well as reflected rays, and these rays may take such angles as to completely illuminate the wider transparency 10. It is evident that the lantern should set back some little distance from the transparency, as indicated for example in 70 Fig. 4, so that the extreme lateral portions of the transparency are fully illuminated, and moreover, the window 16 of the lantern must face the back of the transparency. The means of suspending the lantern may be of 75 any suitable construction; that shown by way of example comprising links 13 jointed to the lantern at its medial plane at front and back, and are hinged upon the horizontal arm 6 which is arranged above and back 80 of the frame 4 for the transparency. As shown in Fig. 4, this arm 6 is formed of a rod which is welded upon the top of the frame 4 and is bent upward and rearward. It is immaterial how the hinged support 6 85 may be attached to the gate 2 so long as it bears a proper relation to the transparency to enable the lantern to properly swing from a position back of the transparency when the gate is down to a position to one side of 90 the transparency when the gate is raised. The glass front 16 of the lantern may be of ordinary plain glass, or if desired it may be of a compound glass such as the transparency but of plain glass so as to merely be 95 substantially non-destructible but not imparting any color.

As a modification of the general construction shown in Figs. 1 and 2 in which the transparency is held rigidly upon the gate 100 2, I have shown both the transparency and the lantern hinged, the swinging capacity of the lantern being materially less than the transparency so as to cause them to separate 105 when the gate is raised, as indicated in Figs. 110 6 and 7. In this construction the gate 2 is provided with a bracket 6^a to which the lantern 5 is hinged by the links 13 just about the same as in the previous case. The transparency 4^a, however, is also hinged by 115 the links 17, the pivotal point being further from the gate 2 than the pivotal point of the links 13 of the lantern. When the gate is down as in Fig. 6, the lantern 5 will be in the same horizontal level as the transparency 4^a and hence will illuminate it, but when the gate is raised, as in Fig. 7, not only does the lantern swing but the transparency 4^a also swings so that these two 120 parts are out of the same horizontal alignment, and as there is no illumination of the transparency it is not observed at night, whereas the white light of the lantern will come into full view.

There are many ways of modifying the 130

details of construction to suit them to special applications, but by way of example I have shown the preferred construction as applied to an ordinary railroad crossing gate. It will also be understood that while it is desirable when the gate is raised to remove the illumination from the danger signal transparency and bring the white light into view, it is not essential that the 5 white light shall be brought into view as the invention may be confined to illumination and non-illumination of the danger signal transparency alone. It will also be apparent that the general construction and relation of the danger signal transparency and the lantern may be employed without the swinging feature of the gate, but this would relate to conditions where constant danger was always present; that is to say, for places 10 which were not thoroughfares.

It will now be apparent that I have devised a novel and useful construction which embodies the features of advantage enumerated as desirable, and while I have in the 15 present instance shown and described the preferred embodiment thereof which has been found in practice to give satisfactory and reliable results, it is to be understood that I do not restrict myself to the details, 20 as the same are susceptible of modification in various particulars without departing from the spirit or scope of the invention.

Having now described my invention, what I claim as new and desire to secure by Letters 25 Patent, is:—

1. In a danger signal, the combination of a reinforced danger signal transparency consisting of two sheets of glass secured together by an interposed binding sheet of 30 adhering material, a metal frame in which the transparency is secured about its perimeter, and a lantern for illuminating the transparency from one side.

2. In a danger signal, the combination of 35 a reinforced danger signal transparency consisting of two sheets of plain glass secured together by an interposed binding sheet of adhering material of a translucent character having therein the danger color, a metal 40 frame in which the transparency is secured

about its perimeter, and a lantern for illuminating the transparency from one side.

3. In a danger signal, the combination of a reinforced signal transparency consisting of two sheets of plain glass directly secured 45 together by an interposed binding sheet of adhering material of a translucent character having part of its surface formed with color to indicate danger and further having the portions of the surface having color and 50 without color so relatively shaped as to produce letters of a word signifying danger.

4. A compound transparency of glass reinforced with celluloid, comprising two sheets of plain glass secured together upon 55 an interposed uniting sheet of celluloid, said sheet of celluloid having a portion of its body formed of pronounced color and another adjacent portion of relatively clear character.

5. In a danger signal, the combination of a rectangular frame of metal, a glass transparency having color for indicating danger held in the rectangular frame said transparency of greater width than height, an 60 arm extending from the rectangular frame upwardly and backwardly, and a lantern suspended from the arm and having a glass front facing the rear of the transparency and arranged at a distance from the transparency said lantern of less width than the 65 width of the transparency and provided with obliquely arranged reflectors.

6. In a danger signal, the combination of a transparency formed with color and having a signal word, with a lantern arranged considerably to the rear of the transparency and of less width than the width thereof, 70 said lantern having a reflecting part and a transparent front facing the transparency 75 whereby the rays of light shall be thrown forward and obliquely in lateral directions through the transparency to fully illuminate 80 its entire width.

In testimony of which invention, I here- 85 unto set my hand.

FRANK SHUMAN.
